UNITED STATES PATENT OFFICE.

J. WILLIAM GROOMES, OF PORTSMOUTH, OHIO.

IMPROVEMENT IN ENVELOPES.

Specification forming part of Letters Patent No. 116,180, dated June 20, 1871.

To all whom it may concern:

Be it known that I, J. WILLIAM GROOMES, of the city of Portsmouth, county of Scioto, State of Ohio, have invented certain Improvements in Letter-Envelopes, of which the following is a specification:

The envelopes now in use are sealed by mucilage on a lap, which is moistened and stuck down on the outside of the envelope, and which can be readily opened by steaming or moistening in any way which will dissolve the mucilage. My invention relates to improvements in envelopes, hereinafter more fully set forth.

Description of Accompanying Drawing.

Figure 1 is a view of my envelope unfolded; Fig. 2, view of my envelope folded.

In the construction of my envelope (see accompanying drawing) the part G of the flap M is folded over the part F on the line n, and attached thereto by mucilage or other equivalent means. The flap M is then folded along the line s, and the side flaps E E provided with slits or openings B B, and flaps D D are folded and the flaps E E are sealed upon the outside of the fold or flap M. The flaps D D are not sealed to the flap M, but are left free to fold over the letter after its insertion into the envelope. C is the top fold of the envelope provided with tongues A A', having waterproof varnish on their outer and mucilage on their inner surfaces. The tongues, after the

insertion of the letter, (the flaps D D being turned over it,) are inserted into the openings B B o o, which are brought opposite each other. The fold G of the flap M serves the double purpose of strengthening the envelope and forming a pocket to prevent the tongues having mucilage on their inner sides from coming in contact with the letter, while the flaps D D, turned over the letter after its insertion, prevent its ready removal.

By the employment of two tongues, A A', near the ends of the top fold C, in lieu of a single tongue in the center of the top fold, as ordinarily used, there is more security in the fastening and greater difficulty in removing a letter, as there is much greater space between a single center tongue and the outer edges of the envelope for the introduction of an instrument for the removal of a letter than when two tongues are employed.

Having thus fully described my invention, what I claim as new, and desire to secure by Letters Patent, is—

The flap M, provided with two slits, o o, and fold G, in combination with the top fold C having tongues A A', and flaps E E having slits B B, substantially as shown and described.

J. WM. GROOMES.
